UNITED STATES PATENT OFFICE

FERNAND LAGUESSE, OF HERSTAL, BELGIUM

TWO-STROKE ENGINE BLOCK

Application filed June 24, 1930, Serial No. 463,509, and in Belgium June 29, 1929.

Two stroke engines are known having opposed pistons which respectively control the opening of the admission and exhaust ports and one of which is rigid with the piston of a charging pump coupled to a delivery chamber or reservoir. In the known arrangements employed this chamber is provided beyond the pump and comprises a chamber surrounding the working cylinder and even adapted to include the crank case.

These arrangements, however, do not permit the variations in pressure which the fuel necessarily undergoes as a result of the change in direction of travel of the pump piston to be balanced.

On the contrary, according to the present invention, a chamber is situated in front of the pump, i. e. on its inlet side and forms an auxiliary chamber or clearance space which is connected to the cylinder of the pump by a relatively long duct. This auxiliary chamber or these auxiliary chambers in the case of a multi-cylinder engine can be arranged in the crank case itself. Under these conditions a column of compressed gas is obtained in this duct which forms an accumulator not only neutralizing the partial vacuum resulting from both the reversal in direction and movement of the compressor piston and the fall in static pressure of the gas when the compression chamber is emptied but permits an increase in the pressure of the gas to be obtained by a dynamic effect, which increases the efficiency of the engine.

The fuel is admitted into the auxiliary chamber by means of a rotary distributor for example which, according to the invention is directly adjacent this chamber for the purpose of obtaining continuity of the movement of the column of gas contained in the duct connecting this chamber to the cylinder.

The accompanying drawing illustrates by way of example, one mode of construction of the invention.

The form of construction chosen is particularly suitable for application to a motor cycle.

Figure 1 is a general diagrammatic section of an engine cylinder and its casing constructed according to the invention.

Figure 2 shows certain diagram outlines.

In Figure 1, a two-stroke engine cylinder 2 guides the movement of two opposed pistons 3 and 4 coupled by rods 5 and 6 to the corresponding crank pins of a crank shaft 7. The cylinder 2 comprises at its upper part a part 2a bored to a larger diameter than that of the cylinder 2 in which bore moves a piston 3a rigid with the piston 3. The system formed by the piston 3a and the cylinder 2a is designed to perform the function of a compressor.

During the downward movement of the piston 3a and under the action of the resulting suction, air is drawn in through a carburettor by the communication of the cylinder 3a through a duct 45a with the chamber 45b of a rotary distributor 46 of any known type, the chamber 45b being for example placed in direct communication with the carburettor.

During the upward stroke of the piston 3a corresponding to the power stroke of the piston 3 and after the closure of the duct 45a by the distributor 46, the carburetted mixture is compressed in the dead space of the cylinder 3a and in a duct 2b adapted to lead the fresh gases towards the admission port 2c in the power cylinder the opening of which port is controlled by the movement of the piston 3.

The operation of the engine takes place upon the known cycle consisting in an admission of the fresh compressed gases through the port 2c towards the end of the mutual separation of the pistons 3 and 4, the compression of these gases during the movement of the said piston towards each other, the ignition of the gases by a sparking plug 8 towards the end of this inward movement, the expansion of the gases producing the power stroke of the pistons 3 and 4, the discharge of the burnt gases through the exhaust port 2d towards the end of this power stroke, the scavenging of the burnt gases by the new charge of fresh gas admitted, as indicated above, and so on.

During this admission stage in which the fresh gases enter the cylinder, the pressure to the right of the port 2c varies between two determined limits. It is a maximum at

the commencement of the admission and a minimum under the influence of the partial vacuum produced by the reversal of the direction of travel of the piston 3a and by the 5 throttling of the transferring orifice. It is without doubt that the rational filling of the cylinder must be obtained when the pressure of the gases at 2c is approximately constant.

The arrangement provided according to 10 the invention for suppressing these oscillations in pressure and rendering uniform the supply by bringing the pressure to a substantially constant ratio, and as near as possible to the pressure at the end of the compression, consists in providing an additional compression chamber 9 connected to the clearance space of the cylinder 2a by a duct 9a. In this way a column of compressed gas is obtained in the latter forming what may be 15 called a feeder, and the initial force of which will tend to neutralize the depressions undergone by the fresh gas during the period of opening of the port 2c. In this way a filling stage of the cylinder 2 is obtained which is 20 as uniform as possible. Naturally the volume of the chamber 9 which is indispensable for supplying the duct 9a and also the section and length of the latter, are chosen in such a way as to ensure that the desired result 25 will be obtained.

As shown in Figure 1, this chamber 9 and the duct 9a are connected between the rotary distributor and the compressor cylinder. Their arrangement at another point will remain moreover within the scope of the invention.

With a view to a possible regulation, the device shown in Figure 1 represents a member 10 in the form of a valve the position of 40 which with respect to a seating 10a is adjustable in such a way that it is possible to obtain at this point a certain throttling of the section of the duct 9.

The diagrams shown in Figure 2, of which 45 only the general outline must be taken into consideration, enable the operation to be observed.

In this figure the abscissæ correspond to the angular displacement of one of the crankpins 50 and the ordinates correspond to pressure to the right of the admission port for the curves a-b-f, a-b-e, a-b-n. The curve g-i-h represents the law for the opening and closing of the port 2c. Previous to the 55 opening at the end of the upward stroke of the piston 3a the compression of the fresh gases in the cylinder 2a is completed in accordance with the curve a-b immediately before the commencement of the opening 60 stage. In the case of a compression chamber of simple form, the expansion stage corresponding to the period of opening of the admission port such as 2c will be represented by a curve b-d which will be extended by a 65 part such as d-e if the opening of the port

continued with a constant value. As this aperture commences to be throttled after this point i at the same time as the change in direction of movement of the compressor piston accentuates the expansion effected, the curve 70 b-d is extended actually by the part d-f.

By means of the arrangement invented, the curve representing the expansion during the admission period is raised, as shown by the curve b-m-n. It is seen that for one and the same initial pressure the final pressure is greater than in the other cases envisaged, corresponding to the known devices with a compression chamber of simple form. On account of the raising of pressure indicated, 75 the case when the cylinder is filled at a constant pressure is more nearly approached, that is to say more favourable conditions are obtained.

Having now particularly described and ascertained the nature of my said invention and in what manner the same is to be performed, I declare that what I claim is:—

1. A two-stroke combustion engine comprising a motive cylinder having admission and exhaust ports, two opposed pistons arranged in said cylinder so as to respectively control said admission and exhaust ports, a crankshaft operatively connected with both pistons, a pump piston formed by an enlargement of the piston controlling said admission ports, a cylinder for said pump piston formed by an enlargement of said motive cylinder, which pump piston and cylinder form a charge introducing pump, an auxiliary chamber forming the principal part of the total compression space of the pump, which chamber is situated before the pump, and a relatively long duct connecting said auxiliary chamber with the pump cylinder.

2. A two-stroke combustion engine comprising a casing, a motive cylinder having admission and exhaust ports, two opposed pistons arranged in said cylinder so as to respectively control said admission and exhaust ports, a crankshaft operatively connected with both pistons, a pump piston formed by an enlargement of the piston controlling said admission ports, a cylinder for said pump piston formed by an enlargement of said motive cylinder, which pump piston and cylinder form a charge introducing pump, an auxiliary chamber forming the principal part of the total compression space of the pump, which chamber is situated in the engine casing before the pump, and a relatively long duct connecting said auxiliary chamber with the pump cylinder.

3. A two-stroke combustion engine comprising a motive cylinder having admission and exhaust ports, two opposed pistons arranged in said cylinder so as to respectively control said admission and exhaust ports, a crankshaft operatively connected with both pistons, a pump piston formed by an enlarge-

ment of the piston controlling said admission ports, a cylinder for said pump piston formed by an enlargement of said motive cylinder, which pump piston and cylinder form a charge introducing pump, an auxiliary chamber forming the principal part of the total compression space of the pump, which chamber is situated before the pump, a relatively long duct connecting said auxiliary chamber with the pump cylinder, and a fuel distributor, directly adjacent said chamber to obtain continuity of movement of the column of gas contained in the duct connecting the chamber to the pump cylinder.

15 Dated this 6th day of May 1930.
